US0D1086692S

(12) United States Design Patent (10) Patent No.: US D1,086,692 S
(45) Date of Patent: * Aug. 5, 2025

(54) CASE FOR HEADPHONES

(71) Applicant: Apple Inc., Cupertino, CA (US)

(72) Inventors: Megan J. Burmeister, Menlo Park, CA (US); Shannon M. McGrath, Los Angeles, CA (US); Teresa Y. Yen, Arcadia, CA (US)

(73) Assignee: Apple Inc., Cupertino, CA (US)

() Term: 15 Years

(21) Appl. No.: 29/879,938

(22) Filed: Jul. 14, 2023

(51) LOC (15) Cl. 03-01

(52) U.S. Cl.

USPC D3/289; D3/303

(58) Field of Classification Search

USPC D3/20, 21, 23, 24, 201, 203.1, 203.5, D3/203.6, 203.7, 203.8, 205, 206, 215, D3/218, 237, 263–265, 270, 271.8, D3/273–276, 294–302, 318, 319, D3/321–323, 901, 903, 305, 315, 316, D3/289, 303; D7/601, 602, 609, 635, D7/637, 638; D9/661, 662, 700, 701, D9/738, 740, 741, 414, 415, 424–427; D12/415, 423–426, 426.1; D13/107, 108, D13/152, 184; D14/203.4, 203.5, 203.6, D14/204, 205, 223, 229, 251, 252, D14/509–511; D24/224–227, 229; D27/172, 186; D99/28
